UNITED STATES PATENT OFFICE.

EDWARD H. ANGLE, OF NEW LONDON, CONNECTICUT.

DENTAL PLIERS.

1,163,196.

Specification of Letters Patent.

Patented Dec. 7, 1915.

Application filed March 20, 1915. Serial No. 15,859.

To all whom it may concern:

Be it known that I, EDWARD H. ANGLE, a citizen of the United States, and a resident of New London, in the county of New London and State of Connecticut, have invented 5 certain new and useful Improvements in Dental Pliers, of which the following is a specification, reference being had to the accompanying drawings.

10 My invention relates particularly to that class of pliers which are designed for use in connection with the art of orthodontia, and is directed especially to the means for holding a tooth-band while being applied to conform 15 to a tooth to which it is to be subsequently attached.

In the art of orthodontia it is highly essential that the tooth-band shall be drawn extremely taut around the tooth to which it 20 is to be adapted, so that it may be caused to accurately conform thereto around approximately one-half of the tooth, while being shaped around the other half by any suitable form of tool, such as my "dental pliers" 25 shown in United States Patent No. 610,840, granted to me September 13, 1898, and as the metal of which tooth-bands are composed is rare and consequently expensive, it 30 is desirable that the strips forming the bands may be as short as possible to avoid waste.

It is the principal object of my invention to provide pliers for holding a tooth-band, which are adapted to present it in a position 35 convenient to be applied to any tooth of the dental arch, and to firmly grasp the extreme ends of the strip forming the band, in such manner that the greatest possible stress may be tensilely applied thereto without the possibility 40 of its accidental release by slipping.

Another object of my invention is to provide band-holding pliers so formed as to afford the free and unobstructed use of a band-forming tool.

45 My invention also includes all of the various novel features of construction and arrangement hereinafter more definitely specified.

In the accompanying drawings, Figure 1 50 is a perspective view of a pair of pliers conveniently embodying my invention; Fig. 2 is a plan view of the pliers shown in Fig. 1;

Fig. 3 is a side elevational view of said pliers as viewed from the lower side of Fig. 2; and Fig. 4 is a transverse sectional view 55 of the beaks taken adjacent to the free ends thereof, on the line 4—4 in Fig. 3, and passing longitudinally through the tooth-band held thereby.

In said figures, the relatively movable 60 members 5 and 6 forming the pliers are pivoted at 7, and respectively have the rearwardly extending handles 9 and 10, and forwardly extending opposed jaws 12 and 13, which have beaks 15 and 16 extended laterally, preferably in forwardly directed, obtuse, angular relation thereto, as best shown 65 in Figs. 1 and 3. The beaks 15 and 16 are provided with slots or slits 17 and 18, respectively extending inwardly through their free ends, and disposed in transverse alignment with each other when said beaks are close together. The slits 17 and 18 are preferably broadened or beveled outwardly 70 toward the outer corners 19 and 20 of the respective beaks, to provide for the easy insertion of the strip forming the tooth-band 21, whose ends are brought together to form the bight 22, embracing the tooth 23, and extended through one of said slits 17 or 18 75 with its extreme terminal portions 24 and 25 respectively bent outwardly in the plane of occlusion of the beaks 15 and 16, as shown 80 in Figs. 2 and 4.

It will be obvious that the gripping bite 85 of the pliers upon the tooth-band is not in the plane of the stress upon the band, but is transverse thereto, thus affording a firm hold thereon which is insured against accidental slipping so long as the beaks 15 and 90 16 are forced in the direction tending to effect occlusion of said beaks.

It is desirable that the bent terminal portions 24 and 25 shall be as short as practicable, and preferably of uniform length, and 95 for this purpose one of the handles 9 or 10 may be provided with the recess 27 into which the end of the strip forming the band may be thrust and bent transversely into the form best shown in Fig. 4.

100 It may be here noted that the provision of a slit in each of the beaks 15 and 16 enables the operator to use the band-holding pliers either right or left hand, and upon either

the upper or lower teeth with convenience, and that the slight forward slant of said beaks 15 and 16 affords easy access to any tooth of the dental arch, with the hand of 5 the operator holding the band-holding pliers, out of the way of the hand manipulating the forming tool.

I do not desire to limit my invention to the precise details of construction and arrangement herein set forth, as it is obvious 10 that various modifications may be made therein without departing from the essential features of my invention as defined in the appended claims.

15 Having thus described my invention, I claim:

1. A pair of pliers having its beaks slitted transversely.
2. A pair of pliers having its beaks extended laterally, and provided with slits 20

Copies of this patent may be obtained for five cents each, by addressing the "Commissioner of Patents, Washington, D. C."

broadening toward the outer edges of said beaks.

3. A pair of pliers having its beaks extended laterally, and having transverse slits opening through their free ends. 25

4. A pair of pliers for holding a tooth-band, having its beaks extended laterally, and provided with slits extended transversely, through which the ends of said band may extend, with its terminals bent in the 30 plane of occlusion of said beaks, and a recess in the handle of said pliers for holding the terminals of said band while being bent.

In witness whereof, I have hereunto set my hand this 18th day of March, A. D., 1915. 35

EDWARD H. ANGLE.
